CLAIM

The ornamental design for shower handle set, substantially as shown and described.

DESCRIPTION

FIG. 1 is a top plan view of a shower handle set showing my new design;

FIG. 2 is a front elevational view thereof;

FIG. 3 is a right side elevational view thereof, the left side being a mirror image of the right side shown;

FIG. 4 is a bottom plan view thereof;

FIG. 5 is a front elevational view of a modified form of the shower handle set shown in FIG. 1;

FIG. 6 is a front elevational view of a second modified form of the shower handle set shown in FIG. 1; and

FIG. 7 is a front elevational view of a third modified form of the shower handle set shown in FIG. 1.

Fig. 1.

Fig. 2.
